UNITED STATES PATENT OFFICE.

AUTHUR HOLMES, OF CANTON, OHIO.

PISTON.

1,311,124.

Specification of Letters Patent. Patented July 22, 1919.

Application filed August 16, 1917. Serial No. 186,510.

To all whom it may concern:

Be it known that I, ARTHUR HOLMES, a citizen of the United States of America, and resident of Canton, in the county of Stark, 5 in the State of Ohio, have invented new and useful Improvements in Pistons, of which the following, taken in connection with the accompanying drawings, is a full, clear, and exact description.

10 This invention relates to certain improvements in pistons and is particularly adapted for use in internal combustion engines of automobiles, motor-boats and the like and this application is filed as a continuation in 15 part of my former copending application, Serial No. 133,918, filed November 28, 1916 for pistons.

In the use of gas engines, the efficiency 20 of the engine depends to a considerable extent upon the rapid cooling of the piston and the cylinder, and the difficulty has been to transfer or conduct the heat particularly from the central portion of the piston, (the 25 hottest part of practically all gas engines) rapidly enough to permit high efficiency of the engine.

The cylinders of such engines have usually 30 been made of cast iron and, to a considerable extent, the pistons have been formed of the same material or at least a material of substantially the same coefficient of expansion as the material of which the cylinder is formed, so that the clearance (perhaps 3 or 35 4 one thousandths of an inch) between the piston and the cylinder will remain practically uniform at all temperatures, preventing rattling and clapping of the piston and causing it at all times to move in substantially accurate axial relation with the cylinder.

40 However, cast iron and other suitable material of like coefficient of expansion is not capable of conducting the heat from the central portion of the piston to the wall of the cylinder with sufficient rapidity to permit high efficiency operation of the engine.

To avoid this difficulty, pistons have 45 recently been formed of material having a high heat conductivity, such as aluminum. The difficulty with pistons of this character lies in the fact that aluminum has with high

heat conductivity also a high coefficient of expansion, substantially double that of cast iron. The use, therefore, of aluminum or 55 material having a different coefficient of expansion from that of the cylinder, in the formation of pistons results in either of two conditions.

First. The piston must be of materially 60 less diameter than the cylinder when cold permitting considerable clearance and resulting in what is generally called "piston slaps" or,

Second. If the clearance is small, the piston 65 and cylinder will seize when hot.

Thus the cast iron piston has a distinct 70 advantage in that its coefficient of expansion is the same as that of the cast iron cylinder for any given change of temperature, while the aluminum piston is much more effective 75 in producing high engine efficiency, due to its assistance in rapidly cooling the cylinder and the engine as a result of its high heat conductivity.

The object, therefore, of this invention is 80 to produce a piston having all the advantages of the high conductivity of an aluminum piston combined with the advantages of a piston formed of a material having the same or approximately the same coefficient 85 of expansion as the cylinder in which it works. This object is accomplished by forming the top portion of the piston exposed to the high temperature of the combustion chamber, of aluminum or similar material of high heat conductivity and giving this portion of the piston a sufficient clearance so it will not seize the cylinder 90 when hot, while the lower portion, of sufficient length to constitute a bearing, to cause the piston at all times, whether hot or cold, to move axially of the cylinder without slapping or rattling, is formed of cast iron or 95 similar metal having approximately the same coefficient of expansion as the cylinder.

The difficulty of constructing a piston of 100 this type arises entirely from the fact that no method has heretofore been devised or known for connecting the two parts of the piston in a manner to permit free expansion and contraction of the two materials.

I believe that I am the first to produce

an operable, efficient piston of this type, due to the method herein shown and described of connecting the two parts at their axes only and allowing symmetrical, uniform 5 expansion radially from the connecting means throughout the entire area of the parts without in any way altering the substantially accurate, circular form of the parts.

10 In the drawings—

Figure 1 is a top plan view of the piston. Fig. 2 is an elevation of the same.

Fig. 3 is a section on line 3—3, Fig. 2.

Fig. 4 is a bottom plan view of the upper 15 section of the piston.

Fig. 5 is a top plan view of the lower section of the piston.

Fig. 6 is a vertical sectional view through 20 a piston of my invention illustrating the different diameters of the section in an exaggerated manner, and showing a portion of a cylinder within which the piston is adapted to move.

As stated, the piston shown in the drawings is adapted for assembly with the usual cylinder *a* of an internal combustion engine, such cylinder being usually formed of cast iron, other similar material being perhaps utilizable.

30 The piston —1—, as shown, is formed in two sections, an upper section —2— of aluminum or other suitable material of high heat conductivity, and incidental to such high conductivity having a coefficient of expansion considerably greater than that of the cast iron cylinder *a* within which it is adapted to work, and a lower section —3— formed of cast iron or other suitable material having a coefficient of expansion the 35 same as that of the cylinder within which the piston works and, therefore, of a coefficient of expansion considerably less than that of the aluminum upper section.

40 Preferably the assembled piston tapers 45 slightly from its lower end toward its upper end, and the aluminum upper section —2— is of slightly less diameter than the lower section —3—.

It will be apparent that the two parts 50 may be of any desired relative length so long as the lower section —3— is of sufficient axial length to constitute a bearing for the piston, causing the same to move axially of the cylinder without slapping or rattling, 55 and in the specific illustration shown, the lower section —3— is formed of cast iron and embodies the radial wrist-pin bosses —4— and —5— near or approximately at its upper end, and preferably a reinforcing 60 flange —6— adjacent its lower end.

This section —3— is provided with a cross wall —7—, of which the upper portion of the bosses —4— and —5— may constitute parts, the intermediate portion between said 65 bosses preferably being arched, as shown, at

—8— and formed with a boss —9— having a central opening disposed axially of the cylinder and internally threaded for a purpose hereinafter described.

The upper section —2— may preferably, 70 as shown, be of inverted cup-shape and having a central, axially-projecting boss —10— formed with a central threaded opening terminating in a frusto-conical seat —11— in which the head —12— of a screw —13— is 75 adapted to be countersunk, the screw passing through and having a threaded engagement with the aligned interiorly threaded openings in the bosses —9— and —10—, and preferably the lower end of the screw 80 may be spun over into engagement with the adjacent arched portion —8— of the cross wall —7— to constitute a permanent rigid connection between the two parts of the 85 piston.

When the bosses —9— and —10— are in firm contact, the circumferential wall —14— of the section —2— rests tightly upon the upper edge of the lower section —3— to constitute a substantial continuation thereof, its radial movement resultant from expansion under varying degrees of temperature relatively to the section —3— being 90 free and unobstructed.

In the form shown, the upper section 95 —2— is provided with the usual circumferential grooves —15— for the reception of piston rings, and the upper portion of the bosses —4— and —5— or the transverse wall —7— may be provided with perforations or openings —16— permitting the passage of lubricant to the wrist-pin bearings.

The section —2— is provided with a series of reinforcing ribs —17— tapering outwardly from the boss —10— and merging 105 into the outer wall of the section to strengthen the wall of the piston directly exposed to the force of combustion within the cylinder (not shown).

It will be apparent that the only connecting means between the two sections of the piston is the bolt —13— arranged substantially axially of said sections and that the outer edges or circular walls of the sections have planular surfaces normal to the axis 110 of the piston, which surfaces are free to move or slide radially relatively to each other under the action of varying temperatures to which the different sections are subjected, and in accordance with their varied 115 coefficients of expansion.

As illustrative of one relative proportionate size of parts, the following may be referred to:

With a cast iron cylinder of $3\frac{1}{2}''$ or $4''$ 125 internal diameter, the section —3— of the piston may have a clearance of 3 or 4 one-thousandths of an inch, while the aluminum section —2— at the greatest diameter may have a clearance of from 6 to 8 one-thou- 130

sandths of an inch, the section —2— being tapered slightly from its lower end or circumference of greatest diameter toward the upper end to account for different degrees 5 of expansion, due to different degrees of heat, to which the respective portions of the piston are subjected, the object being to taper the piston just sufficiently to give the same, under high degrees of heat generated 10 at high speed, an approximately cylindrical exterior adapted to closely fit the interior of the engine cylinder.

With the construction here shown, the section —3— at low temperatures constitutes 15 the bearing for the entire piston, while under high degrees of heat, the entire piston has a substantially continuous cylindrical exterior closely fitting the interior of the engine cylinder throughout the entire length 20 of the piston.

Although I have shown and described one specific form, arrangement and size of sections and one specific means for attaching the same to permit free expansion of both 25 parts, radially of the connecting means, I do not desire to limit myself to the same as various changes may be made in the details of form, construction, size, arrangement, and means of attachment without departing 30 from the spirit of this invention as set forth in the appended claims.

What I claim is:—

1. A piston comprising a substantially cylindrical section having a coefficient of expansion substantially equal to that of the cylinder within which the composite piston is adapted to move, an inverted cup shaped section of relatively high heat conductivity, said sections having concentric axial and peripheral abutting surfaces lying in a plane substantially normal to the axis of the composite piston and means connecting the axial abutting portions permitting free radial expansion of the sections independently of 45 each other.

2. A piston comprising a substantially cylindrical section having a coefficient of expansion substantially equal to that of the cylinder within which the composite piston is adapted to move, an inverted cup shaped section of relatively high heat conductivity, said sections having concentric axial and peripheral abutting surfaces lying in a plane substantially normal to the axis of the composite piston and a bolt extending through and connecting the axial abutting portions of said sections, permitting free radial expansion of the sections independently of each other, the axis of the composite piston 60 lying in said bolt.

3. A piston comprising two sections of different heat conductivity and of different diameters connected at their axes only, and free to expand radially independently of 65 each other.

4. A piston comprising a substantially cylindrical section having a coefficient of expansion substantially equal to that of the cylinder within which the composite piston is adapted to move, an inverted cup-shaped section of relatively high heat conductivity and of less diameter than said cylindrical section, said sections having concentric axial and peripheral abutting surfaces lying in a plane substantially normal to the axis of the composite piston, and means connecting the axial abutting portions, permitting free radial expansion of the sections independently of each other. 70 75

5. A piston comprising an inverted cup-shaped upper section of high heat conductivity and a substantially cylindrical lower section having a smaller coefficient of expansion and being of greater diameter than the cup-shaped section, and means connecting the two sections permitting free radial expansion and contraction of each independently of the other. 80 85

6. A piston comprising an upper section formed of material of high heat conductivity, a lower substantially cylindrical section of greater diameter than the upper section and having a cross wall at its upper end, one of said sections provided with an axial boss extending into contact with the other section, and means positioned substantially axially of the composite piston and extending through said boss and connecting the upper section to said cross wall. 90 95

7. In combination with a cylinder, a piston movable in the cylinder and comprising a cup-shaped upwardly tapered head-portion formed of material of high heat-conductivity and a substantially cylindrical base portion formed of material having a coefficient of expansion substantially the same as the coefficient of expansion of the material of which the cylinder is formed, and means securing said portions together permitting free radial expansion of the body 100 105 of the cup-shaped head independently of said base portion. 110

8. In combination with a cylinder, a piston comprising a head-portion formed of material of high heat-conductivity and a substantially cylindrical base-portion formed of material having a coefficient of expansion substantially the same as the coefficient of expansion of the material of which the cylinder is formed, said portions being of different external diameter and formed of material of different coefficient of expansion, and means securing said portions together permitting free radial expansion of the head-portion independently of said 115 120 125 base-portion.

9. In combination with a cylinder, a piston comprising a head-portion formed of material of high heat-conductivity and a substantially cylindrical base-portion formed 130 135

41
of material having a coefficient of expansion substantially the same as the coefficient of expansion of the material of which the cylinder is formed, said portions being of 5 different external diameter and formed of material of different coefficient of expansion, and means connecting the two portions at substantially the axis of the composite piston permitting free radial expansion and

contraction of each independently of the other.

In witness whereof I have hereunto set my hand this 8th day of August, 1917.

ARTHUR HOLMES.
